COLLAPSIBLE STEEL CENTERING

Louis J. Sarosdy, Beaver Falls, Pa., assignor to
 Koppel Industrial Car and Equipment Company, Koppel, Pa., a corporation of Pennsylvania

Application November 10, 1932, Serial No. 641,996

12 Claims. (Cl. 25—131.6)

My invention pertains to forms for concrete sewer and tunnel work and more particularly that type of form which is supported upon a carrier during the expanding and collapsing operation and is supported upon the carrier while being moved to a new location.

An object of my invention is to provide a form which is easily adjusted into collapsed or expanded position.

Another object of my invention is to provide a novel means for moving the form to collapsed or expanded position.

A further object of my invention is to provide a form adjusting means which may be operated from a position below the form and which in the case of telescopic forms can be readily detached from the form.

In the drawings forming a part of this description is shown a transverse section through a sewer or tunnel with the invert already poured and the arch form in place ready for pouring. In dot and dash lines the form is shown in collapsed position ready for moving to a new location.

Fig. 1 of the drawings shows the preferred form of the invention, illustrating the collapsing device with the inner ends mounted in fixed relation to the carrier; Fig. 2 shows a modification of the invention in which the inner ends of the device are also mounted in fixed relation to the carrier but a different means is provided for varying the length of the compression member; Fig. 3 shows in half section another modification of my invention in which the inner end of the tension member is mounted in fixed relation to the carrier but the inner end of the compression member is slidably mounted on the carrier; Fig. 4 shows in half section a carrier and collapsing device similar to that of Fig. 3 with the provision of anti-friction means between the mounting of the inner end of the compression member and the carrier; Figs. 5 and 6 show enlarged views the mountings for the inner ends of the compression members of Figs. 3 and 4.

In the drawings reference character 1 indicates an invert over which a form 2 is placed ready for pouring of the arch. The form is shown supported upon a carrier 3 and is braced by suitably placed members 4. Disposed on opposite sides of the carrier and connected to the form are mechanisms for expanding and collapsing the form. These mechanisms also serve the purpose of supporting the form upon the carrier.

The form is shown as comprising two halves hingedly connected together at the top of the arch and having the free ends connected to the

carrier. The form may be of any desired contour and can be formed of two or more parts. The particular details of construction may be made to suit the individual need and in the drawings comprises a plurality of arcuate ribs formed of channel shaped members 5 with the ends of the members 5 connected by channel shaped members 6 and 7. The members 5 having one end coped to fit the flanges of the members 6 and the other ends secured to the back of the web of the members 7. A steel lagging 9 is secured to the flanges of the members 5, 6, and 7. The two halves of the form are hinged together by means of the hinges 8 secured to the inner flanges of the members 6. The members 7 serve the purpose of a bearing for the form when in expanded position.

The carrier 3 comprises a suitably braced construction having a plurality of uprights 10 at each side thereof to which the adjusting mechanism is secured. The carrier is preferably mounted upon wheels 11 which run upon tracks 12 provided for that purpose.

It is to be understood that the carrier and form may be of any desired length which is most suitable for the particular structure being poured. In cases where the forms will be required to move around curves it may be found advantageous to make the carrier and form in short sections to facilitate movement around the curves. In this event two or more carriers may be coupled together when pouring the straight sections and two or more sections of form may be coupled together by passing bolts through the webs of the members 5 of two adjacent sections.

On each side of the carrier are mounted a plurality of adjusting and form supporting means which are pivotally connected to the carrier and adjacent ends of the form. The member 13 is pivotally connected to the upright 10 and to a bracket 14 of the form. The member 15 is pivotally connected to the form at the same place as the member 13 and is connected to the upright 10 in spaced relation to the member 13. The members 13 and 15 thus form a V-shaped supporting and adjusting member for the form 2.

In operation the member 13 functions as a tension member guiding the movements of the form and is of a constant length. The member 15 functions as a compression member and its length varies according to whether the form is being collapsed or expanded. To facilitate the changes in length of the member 15 it is comprised of a steamboat ratchet with end portions 15^a and 15^b. The end portion 15^a is preferably bifurcated with the end of the member 13 fitting within the bi-

furcation and permanently secured therein by a ferrule which has its ends flanged outwardly. The apex of the V can then be secured to the member 14 of the form by passing a pin through the bracket 14 and the ferrule. The member 13 is preferably provided at its mid-portion with a turnbuckle so that the V-shaped supporting mechanism may be used upon forms of different diameters or widths.

10 The operation of the form is as follows: the carrier 3 is assembled upon the tracks 12, the ends of the V-shaped supporting member are pivotally mounted upon the uprights 10 of the carrier and the apex of the V-shaped member is secured to the bracket 14 of the form. These V-shaped members are preferably disposed on opposite sides of the carrier and four or more of such members are used, depending upon the length and weight of the form 2. The ratchet 20 of the member 15 is then operated to expand the form to the position shown by full lines in Fig. 1. The bracing 4 is applied to help sustain the form and weight of the concrete to be poured.

25 After the concrete is set sufficiently to permit stripping of the form, the bracing 4 is removed and the ratchets in the member 15 may be operated to shorten the member 15 to collapse the form into the position shown in dot and dash lines. The form may then be moved to a new 30 location and there set up.

35 If desired the form may be made sufficiently strong and the bracing 4 so placed that the V-shaped member may be disconnected from the form 2 and another form mounted upon the carrier in the position shown by dot and dash lines. This collapsed form can then be moved through the forms already in place and set up at the desired location.

40 In Fig. 2 of the drawings is shown a modification of my invention in which the form 2 is mounted upon a carrier 16 by means of a collapsing device comprising a tension member 17 and a compression member consisting of an outer member 18 and an inner member 19. The adjacent ends of the members 18 and 19 are pivotally connected, the free end of the member 18 being pivotally connected to the bracket 14 of the form at a common point of attachment with the tension member 17 and the inner end of the member 19 being pivotally mounted to the upright 20 of the carrier 16. Pivotally mounted on the carrier is a member 21 which is also connected to the members 18 and 19. It will be observed that the member 17 and the members 18 and 19 form a 45 V-shaped member similar to that formed by the members 13 and 15 in the preferred form of my invention illustrated in Fig. 1 of the drawings. The variations in the effective length of the compound member 18-19 is obtained by means of the turnbuckle embodied in the member 21 which when turned in one direction shortens the effective length of the compound member 18-19 and when turned in the other direction increases the effective length of said member. Otherwise, the 50 operation of mounting, expanding and collapsing the form as shown in Fig. 2 is the same as that used with the form shown in Fig. 1. In this connection it will be observed that there is illustrated by means of dot and dash lines the position of the form when in collapsed position. It will be obvious that with the form in this collapsed position it may be moved through previously erected and fully expanded forms from which the V-shaped members have been disconnected.

55 Referring now to Figs. 3 and 4 of the drawings, there is illustrated another modification of my invention in which the compression member is made in one piece and the collapsing and expanding of the form 2 is effected by operation of the ratchet 27 which moves the screw 22 upwardly or downwardly so as to vary the position of the inner end of the compression member 23 to effect the expansion or contraction of the form. The tension member 24 in this modification being 10 pivotally connected to the carrier and the form. In Fig. 3 of the drawings the bracket supporting the ratchet 27 and screw 22 is fixed in relation to the carrier while the bracket, to which the inner end of the member 23 is secured, is free to 15 move vertically on the uprights of the carrier simultaneously with the screw 22 to which it is attached.

20 In the form shown in Fig. 4 the device is in all respects similar to that shown in Fig. 3 with the addition that the bracket 25 to which the inner end of the compression member is attached has mounted thereon rollers 26 which bear against the upright of the carrier and reduce friction as the bracket moves along the upright. 25

25 In Figs. 2, 3, and 4 the connection between the outer ends of the tension and compression members is so constructed that the V-shaped member formed thereby may be readily removed from the form so as to permit the carrier to be used for 30 supporting and moving additional forms into position.

35 It will be observed from Figs. 2, 3, and 4 that the previously erected forms may be suitably braced and the carrier having other forms in collapsed position may be moved through the previously erected forms without interference with the expanded forms or the bracing therefor.

40 Having thus described the invention, what I claim as new and desire to secure by Letters Patent is:

45 1. In combination, a carrier and a collapsible form, means supporting the form upon the carrier, said means comprising a fixed member and a hinged member, said members being pivotally connected together on the form and pivotally mounted in spaced relation on the carrier, and a member pivotally connected to the carrier and to the joint of the hinged member.

50 2. In combination, a carrier and a collapsible form, means supporting the form upon the carrier, said means comprising a V-shaped member at each side of the carrier, having its apex pivotally connected to the form and having one leg of the V movably mounted on the carrier. 55

55 3. In combination, a carrier and a collapsible form, means on each side of the carrier for supporting, collapsing and expanding the form upon the carrier, said means comprising a tension member and a telescoping compression member, 60 said members being pivotally connected together on said form and pivotally mounted in fixed spaced relation on said carrier.

65 4. In combination, a carrier and a collapsible form, means at each side of the carrier for supporting the form upon the carrier, said means comprising a tension member and a hinged compression member, said members being pivotally connected together on the form and pivotally mounted on the carrier. 70

75 5. In combination, a carrier and a collapsible form, means at each side of the carrier for supporting the form upon the carrier, said means comprising a tension member and a hinged compression member, said members being pivotally

connected together on the form and pivotally mounted on the carrier, and a tension member connected to the carrier and the joint of the hinged member.

5 6. In a tunnel and sewer mold in combination, a rigid carrier, a form hinged about a medial line, a device at each side of the carrier forming the sole support of the form including a pair of arms each having one end pivoted in spaced relation upon the carrier, the opposite ends of the arms being pivotally connected together and to the form, each of said arms of each of said pairs including a device for adjustably varying the length of said arm.

10 7. In a tunnel mold in combination, a rigid carrier including spaced vertical members, a jointed form overlying the top and sides of the carrier, V-shaped means including an adjustable arm at each side of the carrier and secured to the form and vertical carrier members to provide the sole support for the form, each of said means having its apex secured to the form and its arms secured in fixed pivotal relation upon the carrier.

15 8. In a tunnel mold in combination, a rigid carrier, a form including a hinged top connection, a connection between the form and carrier at each side of the carrier including a V-shaped member, one arm of which is adjustable, with the apex of the V connected to the form and the free ends of the arms secured to the carrier in fixed spaced relation.

20 9. In a tunnel and sewer mold, in combination, a rigid carrier, a form hinged about a medial line, means at each side of the carrier forming the sole support for the form, each of said means including a plurality of arms each having one end pivoted in spaced relation upon the carrier, the opposite ends of the arms being pivotally connected to the form on a common longitudinal axis of rotation, at least one of said arms includ-

ing a device for adjustably varying the length of said arm.

25 10. In a mold apparatus in combination, a rigid carrier, a form mounted for bodily lateral and collapsing movement about the carrier, pairs of independently adjustable arms at each side of the carrier forming the sole support for the form, one end of each arm being pivotally connected to the carrier and pivotal connections between each of the other ends of the arms and the form.

10 11. In a mold apparatus in combination, a rigid carrier, a collapsible form, means at each side of the carrier forming the sole support for the form and for expanding and collapsing the form about the carrier, each means including a pair of arms 15 disposed between the carrier and the form, said arms having their inner ends pivotally connected in vertical spaced relation on the carrier, and their outer ends pivotally connected to the form in a manner whereby the lower of the two members, which is collapsible, is in compression, and the upper member, which is of constant length, is in tension during the expanding and collapsing movement of the form about the carrier.

15 12. In a tunnel and sewer mold apparatus, in combination, a rigid carrier, a form hinged about a medial line, means at each side of the carrier forming the sole support for the form and for expanding and collapsing the form about the carrier, each means including a pair of arms 20 disposed between the carrier and the form, said arms having their inner ends pivotally connected with the adjacent side of the carrier and in vertical spaced relation, and their outer ends pivotally connected to the form on a common axis of 30 rotation disposed longitudinally of the form, the lower of said arms having a means associated therewith for imparting collapsing and expanding movement to the form about its hinged connection.

40 LOUIS J. SAROSDY.
